HANDBAG

Frank X. Hiltenbrand, Ridgefield, N. J.

Application March 27, 1953, Serial No. 24,229

Term of patent 3½ years

(CL. D87—3)

To all whom it may concern:

Be it known that I, Frank X. Hiltenbrand, a citizen of the United States of America, residing in Ridgefield, county of Bergen, and State of New Jersey, have invented a new, original, and ornamental Design for a Handbag, of which the following is a specification, reference being had to the accompanying drawing, forming part thereof, wherein,

I claim:

The ornamental design for a handbag, substantially as shown.

FRANK X. HILTENBRAND.
